[57] CLAIM

The ornamental design for a fish hook case, as shown and described.

DESCRIPTION

FIG. 1 is a rear elevational view of a fish hook case, showing my new design;

FIG. 2 is a front elevational view thereof in the open position;

FIG. 3 is a perspective view thereof in the open position;

FIG. 4 is a top plan view thereof in the closed position; and,

FIG. 5 a bottom plan view thereof.

The broken line showing of environment is for illustrative purposes only and forms no part of the claimed design.

FIG. 1.

FIG. 2.

FIG. 3.

FIG. 4.

FIG. 5.
